United States Patent Office

Des. 205,583

Patented August 23, 1966

205,583

WAITRESS' COSTUME OR THE LIKE

Harry A. Backus, 370 Neeb Road, Cincinnati, Ohio

Filed July 1, 1965, Ser. No. 85,991

Term of patent 14 years

(Cl. D3—26)

Fig. 1

Fig. 2

FIG. 1 is a front perspective view showing my new design for a waitress' costume, or the like.

FIG. 2 is a rear perspective view of the waitress' costume shown in FIG. 1.

I claim:

The ornamental design for a waitress' costume or the like, as shown.
